UNITED STATES PATENT OFFICE.

FRED LACEY, OF LOWELL, MASSACHUSETTS, ASSIGNOR TO DRAPER COMPANY, OF HOPEDALE, MASSACHUSETTS, A CORPORATION OF MAINE.

WHIP-ROLL-CONTROLLING MEANS.

1,118,430.

Specification of Letters Patent. Patented Nov. 24, 1914.

Application filed February 27, 1914. Serial No. 821,507.

To all whom it may concern:

Be it known that I, FRED LACEY, a citizen of the United States, residing at Lowell, county of Middlesex, State of Massachusetts, have invented an Improvement in 5 Whip-Roll-Controlling Means, of which the following description, in connection with the accompanying drawing, is a specification, like characters on the drawing representing like parts.

This invention relates to means for controlling the operation and effect of the whip roll of a loom. Various devices have been provided for this purpose, but all have a 15 comparatively limited range of control to adapt themselves to varying kinds of fabric being woven so that it is usually customary either to keep a loom at weaving fabrics of similar quality, or if it be changed to fabrics of different quality to provide whip roll controlling means of different characters, and place upon the loom the proper controlling means, according to the character to be woven.

25 In the weaving of all characters of fabrics it is highly desirable that during the shedding the whip roll shall have a yielding movement toward and from the warp sheet to compensate for the varying length of the 30 warp extending from the warp beam to the fell, caused by its deflection from a direct course by the shedding. This yielding control of the whip roll is desirable, therefore, in the very light loosely woven fabrics as 35 well as in the very heavy closely woven fabrics, and in those of intermediate character. The resistance of this yielding movement should, however, be correlated to the character of warp being used, that is to say, if 40 the whip roll be held against the warp by a spring the spring should be much stronger for heavier warp than it is for lighter warp.

In weaving fabrics it is important that at 45 the time of beat up the action of the whip roll upon the warp sheet should be such as to secure the proper tension of the warps according to the fabric to be woven. In very light, loosely woven fabrics the warp sheet should simply be held under light yielding 50 tension by the whip roll, for heavier and more closely woven fabrics the yarn tension on the warp sheet caused by the whip roll should be increased as required, for still more heavy and more closely woven fabrics

the whip roll should be held rigid against 55 the warp sheet at the time of beat up, and for very heavy and very closely woven fabrics the whip roll at the time of beat up should be rigidly and positively moved against the warp sheet to stretch or put extra 60 tension upon the warp sheet. This action of the whip roll according to the character of the fabric being woven is necessary, as is well understood, in order to secure the proper beating up and prevent the formation of thin places, thick places or stripes.

This invention provides means for controlling the whip roll which when applied to a given loom and properly set or adjusted 70 enables the action of the whip roll to be correlated in the applying of tension to the warp sheet during the shedding, and again during beating up to an extremely wide range of fabrics so that with a single mechanism for controlling the whip roll any 75 given loom may be used for weaving different fabrics extending from very light and loosely woven fabrics such, for example, as serims up to very heavy and closely woven fabrics, such as corduroys and heavy ducks, 80 or to any two or more varieties of fabrics within this wide range.

The principles of this invention may be embodied by any skilled mechanic in quite a wide variety of mechanical devices, and the 85 invention is not to be limited in its broad scope to particular mechanical devices. There are disclosed herein five different mechanical devices embodying the principles of this invention as illustrative of the invention, but not as restrictive of its limits.

The nature of the invention will appear more fully from the accompanying description and drawings and will be more particularly pointed out in the appended claims.

90 The drawings show simple and preferred forms of the mechanisms embodying this invention and only so much of the loom as is necessary to an understanding of the invention is illustrated.

100 In the drawings, Figure 1 is a side view of some of the main parts of an ordinary type of loom with a preferred form of this invention applied thereto; Fig. 2 is a view in cross-section of a detail of the mechanism shown in Fig. 1; Fig. 3 is a side elevation of a portion of the lay sword of a loom with another form of the invention, showing

its point of connection to the loom; Fig. 4 is a side view partially in cross-section of the main elements of another form of the invention; Fig. 5 is a side view of the main elements of another form of the invention; Fig. 6 is a side elevation partially in cross section; and Fig. 7 is a plan view of a portion of a loom with still another form of the invention attached thereto.

10 That form of the invention illustrated in Figs. 1 and 2 and which at present is regarded as the preferred form of mechanism embodying the invention is shown in connection with an ordinary type of loom in which 1 is the loom side frame, 2 is the cam shaft, 3 the crank shaft, 4 the lay, 5 and 6 the heddles shown with the shed open, 7 the warp beam, 8 the warp sheet extending from the warp beam through the heddles to 20 the fell 9, 10 the stand for the whip roll rock shaft, 11 seats in the top of the stand for different positions of the said rock shaft, 12 the whip roll rock shaft, 13 the whip roll rocking arm connected to the shaft 12, and 25 provided with seats 14 for adjusting the position of the whip roll with relation to the shaft 12, 15 the whip roll, and 16 the rocker arm connected to the rock shaft 12 which when operated moves the whip roll to and 30 from the warp sheet, all of which parts and their general operation and construction are familiar to those skilled in the art. A cam 17 is mounted on the cam shaft at the side of the loom and acts to swing at each beat 35 up of the lay a lever 18 fulcrumed at 19 on the loom side. A sleeve 20 is pivotally connected at 21 to an intermediate point of the lever 18. A link or rod 22 is pivoted at one end at 23 to the rocker arm 16 and at its opposite end 24 slides in the sleeve 20. A set screw 25 is threaded into the opposite end of the sleeve 20 and locked in adjusted position by a lock nut 26. A collar 27 having a depending lug 28 is loosely mounted adjacent the sleeve 20 on the link 22 and a second collar 29 is adjustably mounted by the set screw 30 on the link 22 while between these collars surrounding the link 22 is a helical spring 31. On the loom side beneath 50 the link 22 is mounted a fixed abutment 32 in the path of the lug 28.

The range of fabrics which may be woven in the loom by a mechanism embodying this invention of which the mechanical devices just described constitute a preferred form may roughly be divided into four main classes. In the first class for the lighter more loosely woven fabrics the collar 27 is moved to the right so that its lug 28 engages 60 on the right hand side of the abutment 32 and the collar 29 is adjusted to such a position along the link 22 as to give the requisite tension of the spring 31 between the collars 27 and 29. In this position the movement of the lever 18 by the cam 17 will not

affect any movement of the link 22 so that the only tension applied to the warp sheet by the whip roll will be that due to the particular tension of the spring 31. Under these circumstances the whip roll is held in 70 yielding engagement with the warp sheet at the time of beat up during the shedding, and also at the time of beat up. In the second class, for heavier and more closely woven fabrics the collar 27 is placed with its lug 28 to the left of the abutment 32 so that the collar 27 abuts the sleeve 20 and is held thereagainst by the spring 31, the tension of the spring 31 being adjusted to the requisite amount by adjusting the collar 29 on the link 22. The set screw 25 is set back to the left so that it will not at any time contact with the end 24 of the link 22. Under these circumstances during the shedding the whip roll will be held against 80 the warp sheet by a yielding action depending upon the tension of the spring 31, and at the time of beat up this yielding action will be increased by the movement of the lever 18 carrying the sleeve 20 along on the 90 link 22 and comprising the spring 31. In the third class or the still more heavy and more closely woven fabrics the parts will be arranged as last described excepting that the set screw 25 will be so adjusted as to be 95 brought into contact with the end 24 of the link 22 at the time of beat up so that in this case at the time of beat up there is no spring or yielding action but the whip roll is brought rigidly and solidly against the 100 warp sheet. In the fourth class or the heaviest and most closely woven fabrics the adjustment of the parts is as last described, excepting that the set screw 25 is still further screwed into the sleeve 20 so that at the 105 time of beat up the parts are not only held rigid but the rod 22 is given an extended movement, thus causing the whip roll acting rigidly against the warp sheet to extend or put an increased tension thereon at the time 110 of beat up. It will thus be seen that the amount of yielding action during the shedding in all of the classes of fabrics may be varied by varying the position of the collar 29 and that the amount of yielding 115 action during the beat up in the first two classes may be varied in the same manner, all in addition to such variations as are provided by shifting the whip roll, in the seats 14 and the rock shaft 12 in the seats 11. 120 This single mechanism, therefore, provides for an almost infinite variety of conditions enabling the loom in a simple manner readily and quickly to be adjusted under an extreme range of conditions to the proper control of the warp sheet by the whip roll during the shedding and during the beating up.

Another form of the invention is illustrated in Fig. 3 in which 33 represents the lay sword of a loom pivoted at 34, the whip 130

roll being indicated at 35 seated in the rocking arm 36, carried by the shaft 37, having depending therefrom the rocker arm 38. A lever 39 is fulcrumed at 40 on a bracket 41 secured to the loom side and is connected at its lower end by a link or actuator rod 42 to the lay sword at a point above its pivot so that the lever is moved upon the beat up. A rod or link 32 is pivoted at 44 to the rocker arm 38 and has its end 45 sliding through a sleeve 46, and through a loose bearing 47 formed at the right hand upper end of the lever 39. A set screw 48 is threaded into a bearing 49 in the left hand upper end of the lever 39, alines with the rod 43 and is locked in adjusted position by the lock nuts 50. The sleeve 46 is mounted to slide in a bracket 51 secured to the loom side and a set screw 52 passing through the bracket enables the sleeve 46 to be locked against movement. A collar 53 is adjustably secured by a set screw 54 to the rod 43 and a helical spring 55 surrounding the rod 43 abuts against the sleeve 46 and the collar 53.

The operation of the construction thus illustrated in Fig. 3 is quite similar to that shown in Fig. 1 for the first class of fabrics, the sleeve 46 will be moved to the right out of the path of the lever 39, and locked in position with the set screw 52; for the second class of fabrics, the sleeve 46 is left free to slide in the bearing 51 and the set screw 48 is adjusted to the left so is at no time in contact with the end 45 of the rod 43, while the lever 39 at the time of beat up moves the sleeve 46 to compress the spring 49; for the third class of fabrics the set screw 48 is adjusted to the right so as to contact with the end 45 of the rod 43 at the time of beat up; and for the fourth class of fabrics the set screw 48 is adjusted still farther to the right so as to give a positive and extended movement to the rod 43 at the time of beat up.

A third form of the invention shown in Fig. 4 is quite similar to that last described. The lever 56 fulcrumed at 57 to the loom side is operated by any suitable means such as the lay sword or a cam or other properly timing and moving part. The rocker arm 58 for the whip roll shaft is shown at 58. The rod 43 is pivoted at 44 to the arm 58 and slides freely at 59 in the upper end of the lever 56, passing midway through a bearing 60 secured to the loom side. A sleeve 61 is mounted to slide in the bearing 60 and a helical spring 62 surrounds the rod 43, abuts against the sleeve 61 and the collar 63 adjustably secured by the set screw 64 to the rod 43. A sleeve 65 is fitted over the rod 43 and the left hand end of the sleeve 61, and is adjustable longitudinally with respect to both, and may be locked to either or both by means of the set screws 66 and 67. The operation of this form of mechanism will be apparent. For the first class of fabrics

both set screws 66 and 67 are unlocked so that the sleeve 61 is not moved by the lever 56, and the only action upon the whip roll is that due to the spring 62. For the second class of fabrics the set screw 67 locks the sleeve 65 to the sleeve 61 in the required longitudinal position so that at the time of beat up the lever 56 moves the sleeve 61 to compress the spring 62. For the third class of fabrics the sleeve 65 is locked by the set screw 66 to the rod 43 in such position that at the time of beat up the lever 56 will through the rod 43 hold the parts rigid. For the fourth class of fabric the sleeve 65 is locked by the set screw 56 to the rod 43 in such a position that at the time of beating up an extended movement will be given the whip roll.

A fourth form of the invention is sufficiently illustrated in Fig. 5. In this form levers 68 are symmetrically located at opposite sides of the loom frame, operated at the beat up through connections with the lay sword or cams or other suitable means, and are fulcrumed at 69 on the loom frame. The whip roll 70 is journaled in bearing blocks 71 mounted to slide in ways formed in longitudinally adjustable bearing frames 72. These bearing frames are adjusted by means of set screws 73 passing through the overhanging flanges 74 of brackets 75 secured to the loom sides, these flanges 74 being slotted for that purpose. Blocks 76 are mounted to slide in the ways in the bearing frame 72 and are provided with oppositely extended lugs 77 which project into the path of the upper ends of the levers 68 which are forked for that purpose. Set screws 78 pass freely through the closed or left hand end of the bearing plate 72 and are locked in adjusted position by the lock nuts 79. Lugs 80 project from the bearing blocks 71 and helical springs 81 surround the opposing ends of the set screws 78 and lugs 80. In the first class of fabrics the bearing plates 72 are adjusted to the right on the bracket 75 and locked by the set screws 73 in such position that the block 76 will abut against the left hand ends of the bearing plates 72 and the lever 68 when vibrated will not strike the lug 77, and the set screws 78 will be retracted so that the tension of the spring 81 will alone be opposed to the movement of the whip roll. In the second class of fabrics the bearing plate 72 will be adjusted to the left in such a position as shown in Fig. 5, but with the set screws 78 retracted so that as the levers 68 vibrate at the time of beat up they will strike the lug 77 and compress the spring 81. In the third class of fabrics the set screws 78 are adjusted to the right so that at the time of beat up when the blocks 76 are moved to the right the set screws 78 will contact with the lugs 80 at 132

the end of the movement and the parts will be rigid. In this construction reliance is had upon the fact that the tension on the warp sheet will keep the whip roll and its bearing block 71 somewhat to the left of the extreme position. In the fourth class of fabrics the set screws 78 are still farther adjusted to the right so that at the time of beat up not only are the parts rigid, but another extended movement is given while rigid to the bearing blocks carrying the whip roll.

A fifth form of the invention is illustrated in Figs. 6 and 7. Therein a rigid shaft 82 is provided suitably supported in brackets or stands 83 at the loom sides. The crank shaft of the loom is indicated at 84 on which is mounted a cam or eccentric 85. The whip roll 86 rests in one of the seats 87 of rocking arms 88. The rocking arm 88 as shown in Fig. 7 forms one end of a bell crank lever, the other arm of which 89 is offset and is provided with a plurality of seats 90. This bell crank lever is journaled on the shaft 82. A rocker arm 91 is provided with the sleeved hub 92 by which it is adjustably secured on the shaft 82 by a set screw 93 while its free end projects in the path of the eccentric 85. An arm 94 is journaled on the sleeve 92 and may be locked thereon in desired rotary adjustment by the set screw 95. This arm 94 is forked at its free end. A rod 96 provided with a loop or hook at its upper end is hung in one of the seats 90 of the arm 89. A sleeve 97 longitudinally slotted at 98 on one side is mounted on the rod 96 and a collar 99 on the sleeve with a set screw 100 threaded into the collar passing through the slot 98 and abutting against the rod 96 so that the collar and the sleeve may be locked in any desired position relatively to each other and to the rod. A helical spring 101 surrounds the sleeve 97 and abuts against the collar 99 at the bottom and a washer 102 resting against the forked arm 94 at the top, the rod 96 passing up through the forked end of said arm 94. In the first class of fabrics the rocker arm 91 is swung out of the path of the eccentric 85 and locked to the shaft 82 by the set screw 93, the arm 94 is then locked in desired position by the set screw 95, the sleeve 97 is dropped down and the collar 99 and sleeve 97 locked to the rod 96 to give the desired tension of the spring 101. The whip roll will then be controlled entirely by the spring. In the second class of fabrics the rocker arm 91 is brought into the path of the eccentric 85 and the arm 94 is locked by a set screw 93 to the sleeve 92, the set screw 93 being withdrawn. The sleeve 97, collar 99 and spring 101 are adjusted as before. Then, at the time of beat up the eccentric 85 through the rocker arm 91 and arm 94 compresses the

spring giving the desired increased tension. In the third class of fabric the adjustment is as last described excepting that the sleeve 97 is slid up and locked on the rod 96 in such a position so that at the time of beat up its upper end will be struck by the washer 102 beneath the forked end of arm 94, thus giving the desired rigidity. In the fourth class of fabrics the adjustment is as last described excepting that the sleeve 97 is locked in a still higher position so that at the time of beat up an extended rigid movement is given to the parts putting the desired increased strength or tension in the warp.

Having fully described my invention, what I claim as new and desire to secure by Letters Patent is:

1. In a loom the combination of a whip roll mounted for movement toward and from the warp sheet, and means either for permitting a yielding movement of, for causing a yielding movement of, for causing a yielding movement ending in a positive movement of, or for causing an extended positive movement of said whip roll against the warp sheet upon the beat up, thereby to conform with the particular requirements of the fabric being woven.
2. In a loom the combination of a whip roll mounted for movement toward and from the warp sheet, and means either for permitting a yielding movement of, or for causing a yielding movement of, said whip roll against the warp sheet upon the beat up thereby to conform with the particular requirements of the fabric being woven.
3. In a loom the combination of a whip roll mounted for movement toward and from the warp sheet, and means either for permitting a yielding movement of, for causing a yielding movement of, or for causing a yielding movement ending in a positive movement of, said whip roll against the warp sheet upon the beat up thereby to conform with the particular requirements of the fabric being woven.
4. In a loom the combination of a whip roll mounted for movement toward and from the warp sheet, and means either for permitting a yielding movement of, for causing a yielding movement of, or for causing an extended positive movement of said whip roll against the warp sheet upon the beat up thereby to conform with the particular requirements of the fabric being woven.

5. In a loom the combination of a whip roll mounted for movement toward and from the warp sheet, and means either for permitting a yielding movement of, or for causing a yielding movement ending in a positive movement of said whip roll against the warp sheet upon the beat up thereby to conform with the particular requirements of the fabric being woven.

particular requirements of the fabric being woven, and means to adjust the resistance of said yielding movement.

19. In a loom the combination of a whip 5 roll mounted for movement toward and from the warp sheet, means either for causing a yielding movement of, or for causing a yielding movement ending in a positive movement of said whip roll against the 10 warp sheet upon the beat up thereby to conform with the particular requirements of the fabric being woven, and means to adjust the resistance of said yielding movement.

20. In a loom the combination of a whip 15 roll mounted for movement toward and from the warp sheet, means either for causing a yielding movement of, for causing a yielding movement ending in a positive movement of, or for causing an extended 20 positive movement of said whip roll against the warp sheet upon the beat up thereby to conform with the particular requirements of the fabric being woven, and means to adjust the resistance of said yielding 25 movement.

21. In a loom the combination of a whip roll mounted for movement toward and from the warp sheet, means either for causing a yielding movement of, or for causing an extended positive movement of said whip 30 roll against the warp sheet upon the beat up thereby to conform with the particular requirements of the fabric being woven, and means to adjust the resistance of said yielding 35 movement.

22. In a loom, the combination of a whip roll mounted for movement toward and from the warp sheet, means either for causing a yielding movement ending in a positive movement of, or for causing an extended positive movement of said whip roll against the warp sheet upon the beat up thereby to conform with the particular requirements of the fabric being woven, and 45 means to adjust the resistance of said yielding movement.

23. In a loom the combination of a whip roll, a movable support therefor, a spring opposing the movement of said support by 50 the warp sheet, means for adjusting the tension of said spring whereby the tension applied to the warp sheet during the making of the shed by the whip roll and when acting at the beat up may be arranged to 55 conform with the particular conditions of the fabric being woven, means actuated upon the beat up to move said support in opposition to the warps, and means for cutting out the action of said support moving 60 means, for causing it to act through the

medium of said spring for causing it to act first through the medium of said spring and then directly through said support, or for causing it to act rigidly and directly through said support, according to the particular conditions required at the time of bear up. 65

24. In a loom the combination of a whip roll, a rocking support therefor, a lever, and means for vibrating the lever in consonance 70 with the beat up, a link pivoted to said rocking support and slidingly connected to said lever, a spring surrounding said link, adjustable means for causing the lever either to have no action on the link, to move the 75 link through the medium of said spring positively to hold the link, or positively to move the link at the time of beat up as required.

25. In a loom the combination of a whip 80 roll, a rocking support therefor, a lever, and means for vibrating the lever in consonance with the beat up, a link pivoted to said rocking support and slidingly connected to said lever, a spring surrounding said link, adjustable 85 means for causing the lever either to have no action on the link, to move the link through the medium of said spring positively to hold the link, or positively to move the link at the time of beat up as required, and means for adjusting the tension 90 of said spring.

26. In a loom the combination of a whip roll, a rocking support therefor, a lever, and means for vibrating it in consonance with 95 the beat up, a sleeve pivoted midway said lever, a link pivoted to said rocking support and entering said sleeve, a set screw adjustable in the opposite end of said sleeve toward and from the end of said link, a collar on said link adjacent said sleeve, a spring abutting said collar, and means for holding the opposite end of said spring adjustably on said link and a relatively fixed abutment to hold the collar out of the path 100 of the sleeve when required, whereby the mechanism may be adjusted according to the particular conditions of weaving to produce light tension, increased yielding tension, rigidity or positive movement of the 105 whip roll against the warp sheet at the time of beat up.

In testimony whereof, I have signed my name to this specification, in the presence of two subscribing witnesses.

FRED LACEY.

Corrections in Letters Patent No. 1,118,430.

It is hereby certified that in Letters Patent No. 1,118,430, granted November 24, 1914, upon the application of Fred Lacey, of Lowell, Massachusetts, for an improvement in "Whip-Roll-Controlling Means," errors appear in the printed specification requiring correction as follows: Page 5, line 63, before the word "for" insert the word *or*; same page, line 87, after the word "requirements" insert the word *of*; and that the said Letters Patent should be read with these corrections therein that the same may conform to the record of the case in the Patent Office.

Signed and sealed this 15th day of December, A. D., 1914.

[SEAL.]

J. T. NEWTON,
Acting Commissioner of Patents.
